UNITED STATES PATENT OFFICE.

WILLIAM J. KOLLMORGEN AND RAYBORN L. ZERBY, OF SOUTH BEND, INDIANA.

PERIODICAL PUBLICATION.

Application filed April 20, 1922. Serial No. 555,698.

To all whom it may concern:

Be it known that we, WILLIAM J. KOLLMORGEN and RAYBORN L. ZERBY, citizens of the United States of America, residing at 5
 5 South Bend, in the county of St. Joseph and State of Indiana, have invented certain new and useful Improvements in Periodical Publications, of which the following is a specification, reference being had therein to 10 the accompanying drawings.

This invention relates to a method of publishing and it has for its object to provide a method whereby small periodicals, such as parish papers, trade papers, house 15 organs and the like may be distributed with current news, data and information at a minimum cost.

Most periodicals of the character indicated carry two distinct sorts of reading 20 matter, viz., permanent matter, i. e., that matter which appears upon a number of successive issues and non-permanent or current matter which appears only in a single issue.

It is, of course, well understood that the 25 principal expense in connection with printing is the setting of the type and if a large number of copies may be printed from a single setting of type the cost per copy will be correspondingly reduced. Under the 30 present method, we employ a cover section adapted to receive the permanent matter, i. e., all matter of a nature adapting it to appear upon a number of successive issues of the periodical and print these in large 35 quantities and utilize this cover section to house a second section which receives the current matter. This current matter may be printed, but, where the issue is small, as in the case of a parish paper, it may be type- 40 written or reproduced by a typewriting duplicating machine.

The cover section may be used wholly or partly for advertising and when used for advertising the revenue derived therefrom 45 will in many instances support the entire cost of the publication. Thus by our method it is possible to give publicity to the main matter in hand as represented by the current material without cost and in some 50 instances with profit to the user.

In the accompanying drawing:

Fig. 1 is a perspective view partly broken

away of a folder illustrating the method; and

Fig. 2 is a plan view of a slightly modified form of folder.

Like numerals designate corresponding parts in both of the figures.

Broadly speaking in carrying out our method we employ a permanent section A and a current section B. The permanent section comprises a four-page folder, the front of which receives the name of the church or other institution publishing the same, as indicated at 5. The inside of the front leaf 6 of the permanent section, the inside of the rear leaf 7 and the outside of the rear leaf 7 are all adapted to receive permanent matter, such as advertising 8. A large number of these permanent cover 70 sections may be printed at a single run and they serve to house the current section B which receives matter, indicated at 9, local to the activities of the church and current to the particular weekly issue in which it 75 appears. The current section B may be merely slipped between the front and rear leaves of the cover section or it may be fastened therein by pasting, stapling or any other way common among the manufacturers of pamphlets. This current section B may comprise one leaf as in Fig. 1 or two leaves as in Fig. 2 or the number of these 80 leaves may be increased, if desired.

It is not essential that all of the inner 85 surfaces of the leaves 6 and 7 be occupied by permanent matter 8 for portions of these inner surfaces may be used to receive current matter, typewritten thereon, if desired.

Having described our invention what we 90 claim is:

A periodical comprising a removable cover section common to a plurality of issues of the periodical comprising a plurality of folded leaves bearing advertising matter 95 upon their inner faces and an insertable current section carrying current matter specific to a single issue of such publication.

In testimony whereof we hereunto affix our signatures.

WILLIAM J. KOLLMORGEN.
RAYBORN L. ZERBY.
